UNITED STATES PATENT OFFICE.

BENJ. CRAWFORD, OF ALLEGHENY CITY, PENNSYLVANIA.

WATER-GAGE OF BOILERS, &c.

Specification of Letters Patent No. 8,787, dated March 9, 1852.

To all whom it may concern:

Be it known that I, BENJAMIN CRAWFORD, of Allegheny city, in the county of Allegheny and State of Pennsylvania, have invented a new and useful Improvement in Water-Gages for Steam-Boilers; and I do hereby declare that the following is a full, clear, and exact description of my said invention, reference being had to the accompanying drawings, which form part of this specification, and in which—

Figure 1 is an elevation of the water gage in connection with one of my improved steam gages. Fig. 2 is a vertical section 15 through Fig. 1 and Fig. 3 is an elevation of the lower bend of the tube A.

Float water gages placed in a chamber adjacent to the boiler and communicating therewith by a steam pipe connected to the 20 top and a water pipe connected to the bottom of both have heretofore been constructed. This arrangement is liable to such weighty objections as to render its employment inadmissible—first, because the sediment in the 25 boiler will seek and settle in the lowest and coolest place, which being the mouth of the water pipe connecting with the gage chamber, the passage between the latter and the boiler will very soon choke up, especially when the 30 boiler is fed with either river or sea water, and therefore the indications of the gage as to the height of water in the boiler can never be relied on without first blowing off the sediment from the connecting pipe 35 through a cock placed at its lowest bend, which would involve an amount of manipulation and inconvenience, entirely incompatible with the use of an instrument of this kind, whose first requisite is reliability as 40 to the correctness of its indications, and the second is the constant, and conspicuous exposition of the state of the water so that in case of an emergency it can be seen clearly and instantaneously. The blowing off involves 45 the frequent agitation of muddy water in the lower part of the gage, which consists of a glass tube and contains the indicator which is seen through the glass. The muddy water thus agitated by blowing 50 off causes the sediment to rise and very soon to deposit on the inner surface of the tube an opaque coating, which prevents the indicator from being seen and thus renders the gage useless until taken apart and 55 cleaned, which cannot be conveniently done except when the fires are out and the boiler

cool. Another evil that results incidentally from the necessity of such blowing off is the liability of the hot water from the upper part of the chamber to settle down into the glass tube and by suddenly and unequally heating the same cause it to break. 60

The object of my invention is to obviate these difficulties in the float gage placed in a separate chamber adjacent to the boiler and communicating therewith, and my invention consists in attaching the glass tube, which forms the lower part of the chamber, to the upper part thereof, at a point, below the water pipe, which connects the chamber with 70 the boiler, the pipe being connected to the boiler some distance from the bottom thereof. By this arrangement the glass tube is secured from sudden changes of temperature by the rising and falling of the water 75 within it, and it is kept cool, so that the glass is not liable to become corroded or by other means rendered opaque on the inner surface. Thus the indications may at all times be clearly seen, and as the communication with the boiler remains free and open 80 and is not liable to be interrupted the indications can be relied upon with the utmost certainty, and the frequent blowing off of the gage chamber thus dispensed with. 85

The water gage as shown in the drawings consists mainly of a float D, of a float chamber E, and of an index tube F, to receive the stem j of the float. The float chamber E may be cylindrical. It is connected at its upper extremity with the boiler by a pipe k that enters therein above the water level. Its lower extremity is also connected with the boiler by a pipe l that enters therein below the water level but 95 above the index tube F, so that the water shall stand at the same level in the float chamber that it does in the boiler. The index tube F appended to the float chamber is made of glass. Its lower extremity is 100 fitted with a cap m, which can be removed when necessary for repairs or other purposes. This cap is provided with a cock which can be opened at will to blow off the water in the tube whenever the sediment accumulates therein. The float D is fitted to move freely in the float chamber. This float is fitted with a stem j which descends into the glass tube, and is fitted with an index i, which rises and falls as the float rises 105 and falls by an increase or diminution of the water in the boiler. A scale G is at-

tached to the side of the tube to show the level of the water in the boiler corresponding with that of the index in the glass tube. In a flue boiler that division of the scale corresponding with the level of the water at the tops of the flues should be noted, as shown in the drawing, and the space above this level may be conveniently divided into inches to show the height of the water in 10 inches above the tops of the flues.

From the above description it is evident that the water in the glass tube will not circulate with that above, as no heat is applied to it, and the hot water in the float 15 chamber will not descend into it on account of its less specific gravity. Water is well known as so bad a conductor of heat that it is hardly necessary to state that the water in the index tube will remain in a cool state. 20 The glass will not therefore be heated. It will consequently remain transparent and

will permit the rise and fall of the index to be clearly seen.

What I claim as my invention and desire to secure by Letters Patent is—

The arrangement of the glass index tube below the point at which the float chamber is connected with the water in the boiler, the water tube connecting with the boiler at some distance from the bottom of the latter, so that it is not liable to become obstructed, which renders the indications of the float certain, while the coolness and quietness of the water in the index tube leaves it transparent so that the index can 35 be seen clearly and conspicuously.

In testimony whereof I have hereunto subscribed my name.

BENJ. CRAWFORD.
